UNITED STATES PATENT OFFICE.

THOMAS BENFIELD, OF NEWARK, NEW JERSEY.

DESIGN FOR A WATCH-CASE.

SPECIFICATION forming part of Design No. 21,486, dated April 19, 1892.

Application filed March 17, 1892. Serial No. 425,369. Term of patent 7 years.

To all whom it may concern:

Be it known that I, THOMAS BENFIELD, a subject of Her Majesty the Queen of Great Britain, residing at Newark, in the county of Essex and State of New Jersey, have invented and produced a new and original Design for Watch-Cases, of which the following is a specification, reference being had to the accompanying drawings, forming part thereof.

10 Figure 1 is a plan view of a watch-case, showing my design. Fig. 2 is a sectional view thereof, taken on the line 2 2 of Fig. 1. Fig. 3 is a similar view taken on the line 3 3 of Fig. 1.

The leading or characteristic feature of my 15 design consists of a series of ribs A and grooves or corrugations B, disposed or arranged as shown in Fig. 1, said ribs A occupying one portion of the lid of the case and the grooves or corrugations B occupying the opposite portion. As will be seen by reference 20 to Fig. 1, the ribs A radiate from the center of the case, spreading out into fan shape, and

are convex in cross-section, as illustrated in Fig. 3. The grooves or corrugations B are parallel, as shown in Fig. 1, and concave in cross-section, as shown in Fig. 2. The several portions may, it is manifest, be engraved, chased, or otherwise ornamented, as desired.

It is apparent that many pleasing effects may be obtained with this design by chasing, 30 engraving, or otherwise ornamenting some of the ribs A and corrugations B and leaving others bright, and that also this design is applicable to lockets and other similar articles.

Having described my invention, what I 35 claim as new, and desire to secure by Letters Patent, is—

The design for a watch-case, as herein shown and described.

THOMAS BENFIELD.
